UNITED STATES PATENT OFFICE

100,140

DESIGN FOR A SHOE OR SIMILAR ARTICLE

Carl G. Wernmark, Hollywood, Calif.

Application March 27, 1935, Serial No. 56,071

Term of patent 14 years

To all whom it may concern:

Be it known that I, Carl G. Wernmark, a subject of the King of Sweden and a resident of the city of Hollywood, in the county of Los Angeles and State of California, have invented, a new, original, and ornamental Design for a Shoe or Similar Article, of which the following is a specification, reference being had to the accompanying drawing forming part thereof,

Fig. 1 is a sectional view on the line 1—1 in Fig. 2, showing in plan view the portion of the shoe including my design; and

Fig. 2 is a side elevation of the shoe, the broken lines merely indicating the outline of a conventional shoe for illustrative purposes.

The design is particularly concerned with the ornamentation of the meeting portions of the shoe sole and upper.

I claim:

The ornamental design for a shoe or similar article, as shown and described.

CARL G. WERNMARK.
